DISPENSING PACKAGE

William John Wells, Buffalo, N. Y., assignor to
 F. N. Burt Company, Inc., Buffalo, N. Y., a corporation of Delaware

Application December 28, 1943, Serial No. 515,953

5 Claims. (Cl. 229—7)

1

This invention relates to improvements in cartons or receptacles for the packaging of articles for use and sale, and more particularly to an improved arrangement of the carton structure for dispensing of such articles.

Some of the objects of the present invention are to provide an improved carton for articles, such as chewing gum, confections, and the like; to provide an improved arrangement for dispensing articles from the carton; to provide a novel discharge outlet for a carton or box in conjunction with means for manually controlling article movements to the outlet; to provide a novel discharge or dispensing outlet for a package or box in association with a closure means whereby the contents of the package or box are retained safely until ready for use.

Another object of the invention is to provide an improved dispensing carton of the class mentioned that is capable of manufacture in large quantity production by means of automatic machinery and factory methods thus lowering production costs.

A further object of the invention is to provide an improved article dispensing carton of the class mentioned that can be manufactured under factory methods entirely from sheet materials such as paper, cardboard, fiberboard, plastic materials, and the like.

Other objects and advantages of the invention will be in part pointed out in the following detailed description of an illustrative but preferred embodiment of the invention, and will be in part obvious as the disclosure proceeds.

The invention accordingly comprises an article of manufacture possessing the features, properties, and the relation of elements which will be exemplified in the article hereinafter described and the scope of the application of which will be indicated in the claims.

For a more complete disclosure of the nature, objects and advantages of the invention, reference is had to the following detailed description of an illustrative embodiment and to the accompanying drawings in which:

Fig. 1 is a front elevation of a carton or box embodying one form of the present invention, the same being shown with the end and closure flaps and tabs ready to be folded into closed positions;

Fig. 2 is a side elevation of the same;

Fig. 3 is a transverse section substantially on line 3—3 of Fig. 1, showing the position of articles in the carton;

Fig. 4 is a perspective view showing the front of the carton with the cover flap closed;

Fig. 5 is a front elevation of the box with the cover flap open and the article discharge passage way opened ready to permit the articles to discharge therethrough;

2

Fig. 6 is a longitudinal section on line 6—6 of Fig. 5; and

Fig. 7 is a section substantially on line 1—1 of Fig. 5, but showing the carton inverted in dispensing position with its front wall flexed to hold certain of the articles from displacement.

Referring to the drawings, the illustrative embodiment of the invention there shown comprises a carton body 10 formed of a blank of proper shape die stamped from suitable material, such as card board, fiber board, any of the well known plastics, or similar sheet material, properly scored or creased and folded into box-shape and retained in assembled position by gluing or adhesively attaching together the overlapping side flaps 11 and 12. The bottom end of the box 10 is formed by side tabs 13 and 14 as extensions respectively of the opposite box sides and which are scored at their bases as indicated at 14' to fold inwardly towards each other to interfit with the end closing flap 15 and tongue or tuck-in flap 16 thereby providing corner sealing and reinforcement, all of which is usual construction in boxes formed by folding shaped blanks. The end flap or wall 15 and tuck-in flap 16 may be defined by scores or weakening creases 15' and 16' and the tuck-in flap may be adhesively attached to the carton back wall in its closed position or it may be merely tucked in and held frictionally as shown in Fig. 6. The top or filling end of the box is likewise arranged to be closed by a pair of side tabs 17 and 18 and an overlying closing flap or wall 20 with its extension tongue or tuck-in flap 21 which is preferably adhesively attached to the carton back wall in its closed position as shown in Fig. 6. Scores or creases 20' form fold lines for the flaps. An outer locking or dispensing controlling cover 22 is scored or creased along spaced parallel lines 23 so that when folded on these lines, one portion or end flap 22' of the cover 22 forms a snug fit against the end flap or wall 20 as a top reinforcement, while the major portion of the cover 22 lies in its normal closing position shown in Fig. 4 against the front or front wall of the box 10 where it is held by entering a locking slot or cut 24 extending through and transversely of the box front. To facilitate this interlocking of the dispensing controlling flap or cover 22 with the slot 24, the free end of the cover 22 is tapered so that the transverse length of the end of the cover 22 is less than the length of the slot 24. Thus, in the closed position shown in Fig. 4, the cover 22 is firmly interlocked to prevent accidental or improper opening of the top flap 20. In order that the articles can be removed from the box in predetermined limited quantities, for example, one at a time as in the illustrative embodiment, an outlet 25 is provided in the front wall of the box at a convenient location to be covered by the dispensing controlling flap 22,

which as here shown, is in close proximity to one corner of the box. This corner or space between the side and end walls of the carton thus forms a positioning corner for positioning each article in dispensing position at the dispensing outlet 25. In the illustrative embodiment shown the size of this outlet 25 is such that only one article can pass therethrough at a time, and the configuration thereof conforms generally to the shape and size of the articles to be packed in the box. A closure tab 26 having the contour of the outlet 25 is hinged to the box in position to normally close the outlet 25. As shown, the closure tab 26 is an integral part of the box blank and the hinge is formed by folding on a scored or creased weakened line 27. This closure 26 is conveniently made by forming cuts or slits 26' extending entirely through the front wall of the container, but leaving integral supporting sections or ties 28. These supporting ties may be positioned at one edge or more than one edge of the closure 26, three such ties being shown positioned at opposite sides thereof. These ties function to support the closure 26 in closed position during packing and shipping and to prevent improper discharge of the articles until the opening 25 is to be used for normally dispensing the articles. When the closure tab 26 is to be opened for dispensing purposes, a relatively slight pressure or pull on the tab 26 adjacent to the ties breaks them and allows the closure tab 26 to be swung to open position on its hinge 27 as shown in Fig. 5.

Movement or feeding of the articles in the carton towards the discharge opening may be controlled at will by the user by deflecting or flexing inwardly that portion of the box front adjacent to the slot 24. The carton wall can thus be flexed due to the inherent resiliency of this wall and it will return to its normal position when pressure is released. But the slot 24 aids in thus flexing the wall and in controlling the movements of the articles.

In order to locate the place on the front wall of the carton that is most effective on which to exert pressure to flex the carton wall inwardly, it is frequently desirable to mark this place or location by an identifying spot or mark 29 as shown in Fig. 5. This identifying spot gives instant notice to the user to exert pressure at this point to flex the wall inwardly so as to control the article dispensing operation. In the illustrative embodiment shown, the carton is dimensioned and the front and back walls thereof are spaced only slightly more than the thickness of the articles so as to retain all of the articles substantially in the same plane or substantially in a single layer within the carton, but the structure is subject to variation in this respect. The articles A to be dispensed in the present embodiment are shown as candy-coated particles of chewing gum or similar confection and the dispensing opening 25 is sized and proportioned so that only one of these articles can pass at one time through the opening.

When it is desired to dispense one or more of the articles from the completely filled and closed carton, the outside closing and dispensing controlling flap 22 is withdrawn from its retained position in the slot 24 and swung back to its open position as shown in Figs. 5 and 6, thus uncovering the dispensing opening 25 which at that time is closed by the closure tab 26 held in its original position by means of the integral ties 28. The ties 28 are then broken by pressure of the thumb

adjacent to the edge of the closure 26 which is then swung back to open position, as shown in Fig. 5. The user then presses upon the pressure location spot 29, thus deflecting the carton wall inwardly as shown at 30 in Fig. 7. This flexing of the wall exerts pressure upon the articles positioned adjacent to the two inner sides of the dispensing opening 25. The flexing of the walls and the pressure upon the articles is facilitated by virtue of the transverse slot 24. By this means the deflected part of the wall is confined and located more effectively toward the dispensing opening. Thus, a holding and retaining or gripping effect is exerted by the deflected wall upon the articles adjacent to the dispensing opening and movement thereof is prevented, but the article A aligned with the dispensing opening is left free to pass through the opening. When in this condition, the carton is tilted or partially inverted and may be shaken or jogged slightly so that the article aligned with the opening is dispensed or expelled into the hand of the user or elsewhere. The remaining articles are retained from movements as long as the pressure on the wall is exerted. When it is desired to remove another article, the carton is positioned with its dispensing opening upwardly and the pressure on the spot 29 released, whereupon the carton wall due to its resiliency, returns to its normal position, whereupon a slight jogging or shaking and tilting of the carton toward the dispensing opening will cause another one of the articles to move into aligned position with the dispensing opening and the article is then dispensed through the opening in the manner above described. When the articles are moving into dispensing position in the positioning corner of the carton, it will be seen that they may be guided either by the end wall or flap 20 or by the side wall adjacent to the dispensing opening 25, dependent upon the direction of the tilting or shaking of the carton. In this way dispensing of the articles may be very easily controlled until the entire contents have been dispensed. As shown in the drawing the inner surface of the front and back carton walls are smooth and unobstructed, permitting the articles in the receiving compartment to move freely from remote positions toward the dispensing opening 25 at the positioning corner. When it is desired to close the carton after a dispensing operation, the flap 26 may be swung into closing position over the opening 25 and the controlling flap then closed and inserted into the retaining slot 24 as shown in Fig. 4. Thus, the flap 22 effectively closes the dispensing opening 25 and retains the flap 26 in its closed position.

It will now be apparent that a complete unitary article dispensing box has been devised which is particularly adapted for dispensing candy coated gum, confections or any other articles. It should be noted that the box can be filled at either end by proper adjustment of the closing flaps, though generally one end only serves for filling purposes. Thus, specifically considered, the box has one filling opening in the top and a separate discharge outlet in one face of the box. There is no escape for the articles except by way of the outlet. Furthermore, the compact assembly makes it easy for pocket use or other carrying means. Although the walls 15, 20 have herein been referred to as end walls, it will be understood that all of the walls extending between the front and back walls including the walls 15, 20 may be termed side walls since it is

obvious that the shape or proportions of the carton may be varied.

Since certain changes may be made in the article herein described and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. A carton for a multiplicity of articles, said carton having a filling opening and having an article-receiving compartment with a front and back positioned respectively at opposite sides of the articles within said compartment and normally maintaining said articles substantially in a single layer, said front being of resilient sheet material with a transverse slot forming an area susceptible of inward yielding flexing by external pressure so as to cause inwardly flexed front to urge certain of said articles in said compartment against said back thus to hold them from moving into dispensing position while another article is being dispensed, said inwardly flexing area having a discharge outlet of a size to dispense the article, said transverse slot being positioned intermediate the bounds of said carton front so as to locate said flexing area to parts of said front having said outlet, a tab connected to said carton for closing said outlet, means to hold the tab temporarily in closed position, and a cover arranged to be superposed on said tab and to enter said slot to be interlocked therewith.

2. In a carton, in combination, carton walls of sheet material cooperating to form a compartment for receiving a multiplicity of articles, two of said walls being side walls angularly disposed to each other to form a positioning corner for the reception and positioning of an article in dispensing position, two others of said carton walls forming front and back walls respectively at opposite sides of said article-receiving compartment, said front wall forming a front of the carton and having a dispensing opening of such a size as to dispense only a single article at a time and positioned substantially at said positioning corner so that an article positioned at said corner in the receiving compartment can pass outwardly through said dispensing opening, each of said angularly disposed side walls serving as a guide to guide the articles in their movements to said positioning corner and being substantially the same width as a dimension of the articles so as to space said front and back walls apart to lie closely adjacent to opposite sides of individual articles in said compartment so as to maintain them normally substantially in a single layer, said angularly disposed side walls extending to points to lie substantially along adjacent sides of said dispensing opening at said positioning corner so as to position the articles at said dispensing opening, the inner surface of said back wall being substantially smooth to permit the articles to move freely toward said dispensing opening, said front wall at an area thereof adjacent to said dispensing opening being resilient and deflectable inwardly by pressure exerted from without so as to restrict the space between said front and back walls and thereby prevent movement of said articles toward said dispensing opening while an article aligned therewith is being dispensed, said area of the front wall being retracted by re-

siliency thereof when the pressure thereon is released whereby an article can move and be guided along either of said angularly disposed walls into dispensing position in said positioning corner.

3. In a carton, in combination, carton walls of sheet material cooperating to form a compartment for receiving a multiplicity of articles, two of said walls being side walls angularly disposed to each other to form a positioning corner for the reception and positioning of an article in dispensing position, another of said sheet walls forming a front of the carton and having a dispensing opening of such a size as to dispense only a single article at a time and positioned substantially at said positioning corner so that an article positioned at said corner in the receiving compartment can pass outwardly through said dispensing opening, each of said angularly disposed side walls serving as a guide to guide the articles in their movements to said positioning corner and being substantially the same width as a dimension of the articles so as to space said front and an opposing wall apart to lie closely adjacent to said articles in said compartment to maintain the latter substantially in a single layer, said angularly disposed side walls extending to points to lie substantially along adjacent sides of said dispensing opening at said positioning corner so as to position the articles at said dispensing opening, the inner surface of said opposing wall being substantially smooth to permit the articles to move freely toward said dispensing opening, said front wall at an area thereof adjacent to said dispensing opening being resilient and deflectable inwardly by pressure exerted from without so as to cause said inwardly deflected front wall to urge certain of said articles in said compartment against said opposing wall thus to grip and hold them against movement toward said dispensing opening while an article aligned therewith is being dispensed, said area of the front wall being retracted by resiliency thereof when the pressure thereon is released whereby an article can move and be guided along either of said angularly disposed walls into dispensing position in said positioning corner, said front wall having a slot intermediate the bounds thereof and defining one side of said deflectable area whereby inward deflection thereof is effectively located adjacent to said dispensing opening, and a closure flap for said dispensing opening swingably attached to the carton.

4. In a carton, in combination, carton walls of sheet material cooperating to form a compartment for receiving a multiplicity of articles, two of said walls being side walls angularly disposed to each other to form a positioning corner for the reception and positioning of an article in dispensing position, another of said sheet walls forming a front of the carton and having a dispensing opening positioned substantially at said positioning corner so that an article positioned at said corner in the receiving compartment can pass outwardly through said dispensing opening, each of said angularly disposed side walls serving as a guide to guide the articles in their movements to said positioning corner, said front wall at an area thereof adjacent to said dispensing opening being resilient and deflectable inwardly by pressure exerted from without so as to restrict movement of said articles toward said dispensing opening while an article aligned therewith is being dispensed, said area of the front wall being retracted by resiliency thereof when the pressure thereon is released whereby an article can move

and be guided along either of said angularly disposed walls into dispensing position in said positioning corner, said front wall having a slot intermediate the bounds thereof and defining one side of said deflectable area whereby inward deflection thereof is effectively located adjacent to said dispensing opening, a swingable tab hinged to the carton for closing said dispensing opening and having a readily breakable tie integral with said front wall to hold the tab temporarily in closed position, and a closure flap for said dispensing opening extending from a carton wall and arranged to be superposed on said swingable tab and to enter said slot in the front wall to be interlocked therewith.

5. In a carton, in combination, carton walls cooperating to form an article receiving compartment and including front, back, and side walls integral with each other and of sufficiently strong resilient sheet material to maintain the carton normally in extended position to receive articles for free movement therein, said front wall having a dispensing opening sized to limit article dispensing at one time to a predetermined quantity, two of said side walls and said back wall extending adjacent to each other to form an article positioning corner substantially at a carton corner adjacent to said dispensing opening, certain of said side walls being angularly disposed to and extending between said front and back walls and being of a width approximating a dimension of the articles thereby to maintain said front and back walls normally spaced apart a distance slightly greater than said article dimension to maintain said articles substantially in a single layer and to provide for free movements

thereof toward said positioning corner, said front wall at an area thereof adjacent to said dispensing opening being resilient and deflectable inwardly by pressure exerted from without to restrict the space between said front and back walls and thereby prevent movements of said articles toward said dispensing opening while an article aligned therewith is being dispensed, said resilient area of the front wall being retracted by resiliency thereof upon release of pressure thereon whereby another article following a dispensing operation can be freely moved and guided in the receiving compartment into said positioning corner, a closure flap integral with a carton wall and movably mounted on the carton to open or close said dispensing opening, and a releaseable retaining flap movably mounted to overlie said closure flap for holding the latter in closed position.
